UNITED STATES PATENT OFFICE.

HARRY E. WEISGERBER, OF ATLANTIC CITY, NEW JERSEY.

DESIGN FOR A ROLLING CHAIR.

SPECIFICATION forming part of Design No. 35,043, dated September 3, 1901.

Application filed August 2, 1901. Serial No. 70,677. Term of patent 7 years.

To all whom it may concern:

Be it known that I, HARRY E. WEISGERBER, a citizen of the United States, residing at Atlantic City, in the county of Atlantic, State of New Jersey, have invented and produced a new and original Design for a Rolling Chair, of which the following is a specification, reference being had to the accompanying drawing, forming part thereof.

10 The leading feature of my design for a rolling chair is first a body having a depending wall on the back thereof and next vertical passages in said wall.

15 In the accompanying drawing, which represents a perspective view of a rolling chair

embodying my design, A designates the body of a chair, and B the wheels thereof.

C designates the back of the chair, and D designates a depending wall on said back. In said wall are vertical passages E, through 20 which the wheels partly protrude.

Having thus described my invention, what I claim as new, and desire to secure by Letters Patent, is—

25 The design for a rolling chair substantially as shown and described.

HARRY E. WEISGERBER.
